Attorney

UNITED STATES PATENT OFFICE.

THOMAS H. SHOOK, OF MEXIA, TEXAS.

KNEE PAD.

Application filed May 29, 1922. Serial No. 564,501.

To all whom it may concern:

Be it known that I, THOMAS H. SHOOK, a citizen of the United States, residing at Mexia, in the county of Limestone and State 5 of Texas, have invented certain new and useful Improvements in Knee Pads, of which the following is a specification.

This invention relates to new and useful improvements in knee pads.

10 The object of the invention is to provide a knee pad which is especially adapted for cotton pickers and others, and which will afford maximum comfort to the wearer.

A particular aim of the invention is to 15 overcome certain disadvantages which tend to defeat the purpose of various knee pads designed for cotton pickers. Among the results accomplished by the invention is the provision of means for supporting the leg 20 of the wearer immediately below his knee, whereby the pressure which is ordinarily concentrated at the knee, is distributed over a larger surface and the discomfort, when the wearer has been kneeling for a period 25 of time, is alleviated. The said supporting means also maintains the leg of the wearer in a slightly inclined position, whereby less pressure is exerted on the toe.

Another object of the invention is to 30 provide a pad which is dished to form an elliptical support for that part of the wearer's knee surrounding his knee cap, and a substantially concentric sump in which the knee cap is received. By such means the weight 35 of the wearer is borne by that portion of his knee which rests on the elliptical support and the knee cap is relieved. A particular feature resides in a well located in the sump, which has a cushioning effect and 40 tends to relieve any pressure on the point of the knee cap.

A further object is to provide a knee pad which is simply constructed and which may be manufactured at a comparatively low 45 cost.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is a side elevation of a knee pad 55 constructed in accordance with my inven-

tion, showing the same fastened on the leg of a wearer in kneeling position,

Fig. 2 is an enlarged plan view of the pad, and

Fig. 3 is a vertical longitudinal sectional view on the line 3—3 of Fig. 2.

In the drawings the numeral 10 designates a substantially rectangular U-shaped outer casing or shoe, which is preferably made of heavy, tough, flexible material, such as 65 leather, and slit inwardly from each side, whereby the same may be turned up to provide an end 11, as is shown in Figs. 1 and 2. The slit portions of said end overlap the sides of the shoe and are fastened 70 thereto by rivets 12 or the like, thereby securing the said end in place.

A removable pad is adapted to fit snugly in the said shoe and is composed of a casing 13 which is preferably made of heavy fabric 75 and filled with a suitable stuffing 14. The forward portion of the pad is dished to form an elliptical support 15 and a substantially concentric sump 16. The rear portion of the pad constitutes a transverse 80 supporting bridge 17 for supporting the leg of the wearer immediately below his knee. A well 18 is located at the forward end of the sump and a particular advantage 85 is had thereby. It has been found that said well which causes a cushioning effect tends to relieve any pressure exerted on the point of the knee cap.

One side of the shoe 10 carries a plurality of straps 19, adapted to extend over the 90 wearer's leg and engage in buckles 20 fastened to the other side, thereby securing the pad in place, as is shown in Fig. 1.

It is pointed out that when the wearer is 95 kneeling his knee cap is received in the sump 16, while his weight is borne by that portion of his knee surrounding his knee cap and which rests on the elliptical support 15. The transverse bridge 17 supports his leg immediately below the knee, thus distributing the pressure of the wearer's 100 weight over a larger surface and keeping the leg in a slightly inclined position whereby a great deal of pressure is relieved at the toe, all of which will be readily seen in Fig. 1.

It is further pointed out that a cushioning effect is had by the well 18 and the knee cap is relieved from contact with the pad at its point.

It will be seen that a knee pad constructed in accordance with the invention affords maximum comfort to the wearer, and the same is highly desirable by cotton pickers because of its simple and comfortable features.

Various changes and modifications may be made without departing from the spirit of the invention.

10 What I claim, is:

In a knee pad, a casing, a pad composed of a cover and filling material to maintain its configuration, said pad having a trans-

verse supporting bridge at the rear and a concave portion extending forwardly therefrom to receive the knee cap with a further depression at the front of its base forming an air cushion and surrounded by an annular face disposed below the horizontal plane of said bridge to support the knee about the cap thereof, and means for securing the pad upon the leg of a wearer.

15 20
In testimony whereof I affix my signature.

THOS. H. SHOOK.
